[57] CLAIM

The ornamental design for a shoe heel, as shown and
described.

DESCRIPTION

FIG. 1 is a bottom plan view of a shoe heel showing my
new design;

FIG. 2 is a right side elevational view, the left side being
a mirror image thereto;

FIG. 3 is a top plan view thereof;

FIG. 4 is a front elevational view thereof; and

FIG. 5 is a rear elevational view thereof.
